UNITED STATES PATENT OFFICE.

JOHN H. SCHROEDER, OF CHARLESTON, SOUTH CAROLINA.

SIGNAL.

Application filed September 21, 1925. Serial No. 57,649.

To all whom it may concern:

Be it known that I, JOHN H. SCHROEDER, a citizen of the United States, residing at Charleston, in the county of Charleston and State of South Carolina, have invented a new and useful Signal, of which the following is a specification.

This invention aims to provide a simple means whereby a moving railroad train or other vehicle, on a track, may operate signals located on opposite sides of the track, along a highway, thereby to admonish persons proceeding along the highway, that a train is approaching, the signal or semaphore being moved to danger position as the train approaches, and being moved to safe position after the train has passed.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:—

Figure 1 is a plan wherein parts are broken away; Figure 2 is a side elevation wherein parts are broken away; Figure 3 is an elevation showing the parts which are connected immediately to the semaphore; Figure 4 is a plan showing certain of the operating mechanisms which are located adjacent to the track; Figure 5 is an elevation showing another of the mechanisms which are located adjacent to the track; Figure 6 is an elevation showing the train-carried operating means.

The numerals 1 and 2 designate the rails of a track, the track being crossed by a highway 100, as shown in Figure 1. The rails 1 and 2 are supported on ties 3 carrying guides 4 wherein a rigid operating member, such as a rod, is mounted for right-line reciprocation. A slotted arm 6 is connected to the operating member 5 and extends beneath the rail 1, the arm 6 receiving a projection 7 on a horizontally movable bell crank lever 8 fulcrumed at 9 between the

rails 1 and 2, and referred to hereinafter as the third bell crank. The third bell crank lever 8, like other bell crank levers hereinafter mentioned, may be in the form of an approximately triangular plate. A rigid connection 10 is pivoted at 11 to the third bell crank lever 8 and is pivoted at 12 to a sixth bell crank lever 14 fulcrumed at 15, outside of the rail 2, the sixth bell crank lever being connected at 16 to a rod 17 or the like, to which is united a flexible element 18 connected to the lower end of a weighted car-operated actuating lever 19, mounted to swing vertically, and fulcrumed at 20, intermediate its ends, the lever 19 being located outside of the rail 2, and being referred to as the first operated actuating lever.

The operating member or rod 5 carries a slotted arm 21 which extends beneath the rail 1, the slotted arm 21 cooperating with a projection 22 on a second horizontally movable bell crank lever 23, fulcrumed at 24 between the rails 1 and 2, the lever 23 being pivotally connected at 25 to a rod 26 or the like, the rod 26 being pivoted at 27 to a vertically movable first bell crank lever 28 fulcrumed at 29 on a support or post 30 located outside of the rail 2, an upwardly extended rigid connection 31 being pivoted at 32 to the first bell crank lever 28, and being pivoted at its upper end, as at 33, to one end of a semaphore 34, the semaphore 34 being fulcrumed intermediate its ends, as at 35, on the post 30, the semaphore 34 being equipped near to its free end with a reflector 36 adapted to be lighted up by the head lamps of approaching vehicles.

The operating member or rod 5 carries an inwardly extended slotted arm 37 prolonged beneath the rail 1 and receiving a projection 38 on a fourth bell crank lever 39 fulcrumed at 40 between the rails 1 and 2 and connected pivotally at 41 to a rod 42 or the like, which is connected pivotally to a horizontally movable fifth bell crank lever 43 fulcrumed at 44 outside of the rail 2, and pivotally connected at 45 to a rod 46 which is pivotally connected at 47 to the lower end of a vertically swinging intermediate lever 48 fulcrumed between its ends as at 49, outside of the rail 2, a rod 50 being pivoted at 51 to the upper end of the intermediate lever 48, the rod 50 being connected to a chain 52 or other flexible element, which is united at 53 with the lower end of second car-oper-

ated actuating lever 54 fulcrumed intermediate its ends as at 55, the actuating levers 54 and 19 being located on the same side of the track 1—2, and on opposite sides of the highway 100.

The operating member or rod 5 carries an outwardly extended slotted arm 56 cooperating with a projection 57 on another bell crank lever 58 located outwardly of the rail 1, and fulcrumed at 59 for horizontal swinging movement, said other bell crank lever 58 being pivoted at 61 to a rod 60 which is connected by a mechanism 62, like that shown in Figure 3, and hereinbefore described, with a semaphore 63, constructed like the semaphore 34, and mounted on a post or support 64, the posts 64 and 80 being located on opposite sides of the highway 100, and on opposite sides of the track 1—2.

In Figure 6, the numeral 65 designates a locomotive car or other vehicle, provided with a frame 67, the frame including inclined sides 68 adapted to engage the levers 19 and 54.

Suppose that a train is moving to the left in Figure 1. Then, one of the inclined sides 68 on the frame 67 that is carried by the locomotive 65, engages the first car-operated actuating lever 30 and tilts the same. The flexible element 18 and the rod 17 exert a pull on the sixth bell crank lever 14 and tilt the bell crank lever on its fulcrum 15. From the sixth bell crank lever 14, motion is transmitted by the connection 10 to the third bell crank lever 8, that lever swinging on its fulcrum 9, and the projection 7 on the said lever causing the rod 5 to move to the left, through the instrumentality of the slotted arm 6. When the rod 5 moves to the left, the slotted arm 21 moves to the left also, the projection 22 swinging the second bell crank lever 23, the bell crank lever 23 exerting a thrust on the rod 26, the rod 26 swinging the first bell crank lever 28 on its fulcrum 29, the rod or connection 31 being raised, and causing the semaphore 34 to swing downwardly on its fulcrum 35, into the danger position shown in Figure 2 of the drawing. At the same time, the arm 56 moves to the left, and, through the instrumentality of the said other bell crank lever 58 and the connection 60, together with the mechanism indicated at 62, the semaphore 63 is lowered into a danger position. Persons approaching the track 1—2, therefore, on the highway 100, from opposite directions, are advised that a train is moving along the track 1—2.

After the train has passed the highway 100, one of the parts 68 of the frame 67 on the locomotive 65 engages the second car-operated actuating lever 54 and tilts that lever on its fulcrum 55, the flexible element 52 and the rod 50 exerting a pull on the intermediate lever 48 and swinging the lever

48 on its fulcrum 49, the connection 46 swinging the fifth bell crank lever 43, and motion being transmitted from the fifth bell crank lever 43 to the fourth bell crank lever 39, the projection 38 on the fourth bell crank lever 39 cooperating with the arm 37 on the rod 5, to move the rod 5 to the right and to restore the semaphores 34 and 63 to lowered, or safe positions.

Owing to the fact that the flexible elements 18 and 52 are provided, a train may back up on the track 1—2 without breaking the operating mechanism, the car-operated actuating levers 54 and 19 swinging readily on their fulcrums.

A car-operated actuating member 69, in the form of a lever, is fulcrumed intermediate its ends on a post 72 or the like, located outwardly of the rail 1, the lower end of the lever 69 being connected to a flexible element 70, which is joined at 71 to the sliding rod or operating member 5. The car-operated lever 69 is located about opposite to the second car-operated lever 54. The showing of the lever 54 in Figure 5 will suffice to indicate how the lever 69 is made. A similar car-operated actuating lever 73 is fulcrumed intermediate its ends on a post 74 located outwardly of the rail 1, the car-operated lever 73 being disposed about opposite to the first car-operated lever 19. The lever 73 is connected by a flexible element 75 and rod 76 with the upper end of an intermediate lever 78 fulcrumed between its ends on a post 79 or the like, located outwardly of the rail 1, the lever 78 being pivoted at its lower end to a rigid link 80 which, in its turn, is pivotally mounted at 81 on the rod 5.

A train moving to the right on the track 1—2, operates the lever 69, the flexible element 70 drawing the operating member or rod 5 to the left, and actuating the semaphores 34 and 63 to danger position, in the way hereinbefore described.

When the train passes to the right of the highway 100 in Figure 1, the mechanism shown in Figure 6 cooperates with the lever 73, the flexible element 75, the rod 76, the intermediate lever 78 and the link 80 to move the rod 5 to the right and to restore the semaphores 34 and 63 to safe position, the flexible connections 70 and 75 permitting the train to back up, in the way hereinbefore mentioned in connection with the parts 18 and 52.

What is claimed is:—

1. The combination with a track including rails, and a highway crossing the track, of a support disposed along the highway at one side of the track, a semaphore mounted intermediate its ends on the support to swing vertically, a first bell crank fulcrumed on the support to swing vertically, second, third and fourth bell cranks fulcrumed between

the rails to swing horizontally, fifth and sixth bell cranks fulcrumed to swing horizontally and outwardly of one of the rails, a connection between the third and sixth bell cranks, a connection between the fourth and fifth bell cranks, a rigid operating member mounted for right-line sliding movement in a direction parallel to the track and located outwardly of the other of the rails, rigid arms projecting inwardly from the operating member beneath said other rail, the arms being slidably engaged, respectively, with the second, third and fourth bell cranks, first and second car-operated actuating levers fulcrumed intermediate their ends for vertical swinging movement and disposed on opposite sides of the highway outwardly of said one rail, a connection between the lower end of the first car-operated lever and the sixth bell crank, an intermediate lever mounted between its ends for vertical swinging movement, a connection between the upper end of the third lever and the lower end of the second car-operated lever, and a connection between the lower end of the intermediate lever and the fifth bell crank.

2. The combination with a track including rails, and a highway crossing the track, of a support disposed along the highway at one side of the track, a semaphore mounted

intermediate its ends on the support to swing vertically, a first bell crank mounted to swing vertically on the support, a connection between the first bell crank and one end 35 of the semaphore, a rigid operating member mounted for right-line sliding movement outwardly of one of the rails, another bell crank mounted for horizontal swinging movement outwardly of the operating member, a connection between said other bell crank and the first bell crank, an outwardly projecting arm on the operating member and slidably engaged with said other bell crank, car-operated actuating levers disposed on opposite sides of the highway, along the track, and fulcrumed intermediate their ends for vertical swinging movement, a flexible connection between one car-operated lever and the operating member, an intermediate lever fulcrumed between its ends for vertical swinging movement, a flexible connection between the upper end of the intermediate lever and the other car-operated lever and a rigid connection pivoted to 50 the lower end of the intermediate lever and to the operating member.

In testimony that I claim the foregoing as my own, I have hereto affixed my signature.

JOHN H. SCHROEDER.
